(57) **ABSTRACT**

A suction apparatus includes a support portion, a plurality of suction holes formed in the support portion, a suction mechanism configured to perform suction from an outer side of the support portion toward an inner side through the plurality of suction holes, a lighting unit provided on the inner side of the support portion for each region of the support portion, a light transmitting portion configured to transmit light emitted by the lighting unit to the outer side of the support portion, and a control unit configured to control the lighting unit, in which the control unit makes a lighting state of the lighting unit corresponding to a suction region in which suction at the support portion is enabled different from a lighting state of the lighting unit corresponding to a non-suction region in which the suction at the support portion is disabled.

SUCTION APPARATUS AND PRINTING APPARATUS

The present application is based on, and claims priority from JP Application Serial Number 2021-106473, filed Jun. 28, 2021, the disclosure of which is hereby incorporated by reference herein in its entirety.

BACKGROUND

1. Technical Field

The present disclosure relates to a suction apparatus and a printing apparatus.

2. Related Art

A suction apparatus is known in which a suction force is generated in suction holes formed in a suction plate on which a medium is placed to suck the medium on the suction plate (see JP-A-2017-154442).

According to JP-A-2017-154442 above, the number of suction holes in which the suction force is generated is controlled by moving a suction control plate movably arranged for the suction plate.

The user needs to place the medium on the suction plate in a region in which the suction holes in which the suction force is generated are concentrated, that is, a region in which effective suction holes are concentrated.

However, it is difficult for the user to place the medium in an appropriate position because he or she does not know which suction holes are effective.

SUMMARY

A suction apparatus includes a support portion configured to support a medium, a plurality of suction holes formed in the support portion, a suction mechanism, when a side, on which a medium is located, of the support portion is an outer side and a side opposite to the outer side of the support portion is an inner side, configured to perform suction from the outer side of the support portion toward the inner side through the plurality of suction holes, a lighting unit provided on the inner side of the support portion for each region of the support portion, a light transmitting portion configured to transmit light emitted by the lighting unit to the outer side of the support portion, and a control unit configured to control the lighting unit, in which the control unit makes a lighting state of the lighting unit corresponding to a suction region in which suction at the support portion is enabled different from a lighting state of the lighting unit corresponding to a non-suction region in which the suction at the support portion is disabled.

A printing apparatus includes a support portion configured to support a medium, a plurality of suction holes formed in the support portion, a suction mechanism, when a side, on which a medium is located, of the support portion is an outer side and a side opposite to the outer side of the support portion is an inner side, configured to perform suction from the outer side of the support portion toward the inner side through the plurality of suction holes, a lighting unit provided on the inner side of the support portion for each region of the support portion, a light transmitting portion configured to transmit light emitted by the lighting unit to the outer side of the support portion, a printing unit configured to perform printing on the medium supported by the support portion, and a control unit configured to control the lighting

2

unit, in which the control unit makes a lighting state of the lighting unit corresponding to a suction region in which suction at the support portion is enabled different from a lighting state of the lighting unit corresponding to a non-suction region in which the suction at the support portion is disabled.

BRIEF DESCRIPTION OF THE DRAWINGS

10 FIG. 1 is a block diagram simply illustrating a configuration of a printing apparatus.

FIG. 2 is a diagram simply illustrating the configuration of the printing apparatus including a support portion viewed from above and viewed from the side.

15 FIG. 3 is a flowchart illustrating lighting/suction control processing.

FIG. 4 is a partial cross-sectional view illustrating a first region on a support surface of the support portion and a first internal space.

20 FIG. 5A is a diagram for describing a difference in visibility between a suction region and a non-suction region in a first example, FIG. 5B is a diagram for describing a difference in visibility between the suction region and the non-suction region in a second example, and FIG. 5C is a diagram for describing a difference in visibility between the suction region and the non-suction region in a third example.

FIG. 6 is a diagram for describing a fourth example.

FIG. 7 is a diagram for describing a fifth example.

30 DESCRIPTION OF EXEMPLARY EMBODIMENTS

35 Embodiments of the present disclosure will be described below with reference to the accompanying drawings. Note that each of the drawings is merely illustrative for describing the embodiment. Since the drawings are illustrative, proportions and shapes may not be precise, match each other, or some may be omitted.

40 FIG. 1 simply illustrates a configuration of a suction apparatus 10 according to an embodiment. Here, the suction apparatus 10 will be described as a printing apparatus 10.

The printing apparatus 10 includes a control unit 11, an operation receiving unit 13, a communication IF 14, a 45 lighting unit 15, a suction pump 16, a printing unit 17, and the like. The operation receiving unit 13 may include a display unit such as a liquid crystal display or an organic EL display for displaying visual information. IF is an abbreviation for interface. The control unit 11 is configured to include one or more ICs having a CPU 11a as a processor, a ROM 11b, a RAM 11c, and the like, another non-volatile memory, and the like.

50 In the control unit 11, the processor, that is, the CPU 11a controls each unit of the printing apparatus 10 by executing arithmetic processing in accordance with one or more programs 12 stored in the ROM 11b, the other memory, or the like, using the RAM 11c or the like as a work area. That is, the control unit 11 can execute lighting control for controlling the lighting unit 15, suction control for controlling a suction mechanism, and printing control for controlling the printing unit 17, separately. The printing apparatus 10 implements a suction method and a printing method. Note that the processor is not limited to a single CPU, and may be a configuration in which a plurality of CPUs or a hardware circuit such as an ASIC executes the processing, or may be a configuration in which the CPU and the hardware circuit cooperate to execute the processing.

The operation receiving unit **13** is a device for receiving an operation and input by a user, for example, a physical button, a touch panel, or a keyboard. The touch panel is used as one function of the display unit.

The communication IF **14** is a collective name for one or a plurality of IFs for coupling the printing apparatus **10** with an external terminal by wire or wirelessly in accordance with a prescribed communication protocol including a known communication standard. The printing apparatus **10** can communicate with an external terminal such as a personal computer (PC), a network server, a tablet terminal, or a smartphone through the communication IF **14**.

The lighting unit **15** is a collective name for light sources located on the inner side of the support portion **20**, as described later. The light source can be, for example, an LED or a fluorescent tube.

The suction pump **16** corresponds to the suction mechanism for sucking a medium placed on the support portion **20** on the support portion **20**. The suction mechanism may include the suction pump **16**, a tube coupling the suction pump and a space to be sucked.

The printing unit **17** includes a printing head **19** and a head moving unit **18** that moves the printing head **19**. The head moving unit **18** can move the printing head **19** two-dimensionally for a surface of the support portion **20** by using power of a motor. The printing head **19** prints an image on a medium supported by the support portion **20** by ejecting a liquid such as ink from a nozzle (not illustrated) in an ink jet system. The medium is typically paper, but may be any material other than paper as long as the material is printable by the printing head **19**.

FIG. 2 simply illustrates a configuration of the printing apparatus **10** including the support portion **20** viewed from above and viewed from the side. The support portion **20** is a table for supporting the medium. The support portion **20** may be referred to as a support table, a document table, a flatbed, a suction plate, a platen, or the like. The support portion **20** has a support surface **21** extending in a first direction D1 and a second direction D2 orthogonal to or substantially orthogonal to the first direction D1. The user places the medium on the support surface **21**. "Viewed from the side" here means "facing the second direction D2".

In FIG. 2, a plurality of small circles on the support surface **21** indicate a plurality of suction holes **22**. The suction hole **22** extends through the support surface **21** and couples the outer side of the support portion **20** and the internal space. A side where the medium is located with respect to the support portion **20** is the outer side, and a side opposite to the outer side with respect to the support portion **20** is the inner side. The suction pump **16** achieves suction from the outer side to the inner side of the support portion **20** through the suction hole **22** by sucking air in the internal space of the support portion **20**. By such suction, the medium placed on the support surface **21** of the support portion **20** is sucked on the support surface **21**. By sucking the medium on the support surface **21**, curling and floating of the medium are corrected and the posture of the medium is stabilized, thereby improving the printing quality.

The head moving unit **18** is located above the support surface **21**. The head moving unit **18** supports the printing head **19**. The head moving unit **18** is long in the second direction D2 and has a length longer than a width of the support portion **20** in the second direction D2. The head moving unit **18** can reciprocate along the first direction D1 while supporting the printing head **19**. In addition, the head moving unit **18** supports the printing head **19** so that the printing head **19** can reciprocate along the long side direc-

tion of the head moving unit **18**, that is, the second direction D2. The control unit **11** achieves two-dimensional movement of the printing head **19** for the support surface **21** by controlling the reciprocating movement of the head moving unit **18** along the first direction D1 and the reciprocating movement of the printing head **19** along the second direction D2 by the head moving unit **18**.

FIG. 3 illustrates a flowchart of the lighting/suction control processing executed by the control unit **11** according to the program **12**.

In step S100, the control unit **11** identifies a "suction region" in which suction is enabled and a "non-suction region" in which suction is disabled in the support portion **20**. That is, the control unit **11** grasps which region of the support surface **21** of the support portion **20** is to be used as the suction region. In the embodiment, the support surface **21** is divided into a predetermined number of regions in advance, and the control unit **11** recognizes the position and range of each region. Since any region other than the suction region is the non-suction region, the control unit **11** can identify the suction region and the non-suction region when either the suction region or the non-suction region is known.

For example, the control unit **11** identifies the suction region according to the size of the medium to be printed. The control unit **11** acquires printing instructions by operation of the operation receiving unit **13** by the user or by communication received from an external terminal via the communication IF **14**. When the printing instructions include information indicating the paper size, the entire region of the support surface **21** may be identified as the suction region, or part of the region of the support surface **21** may be identified as the suction region, depending on the size indicated by the instructions.

Alternatively, the control unit **11** may identify the suction region and the non-suction region by receiving an input that directly specifies the suction region and the non-suction region from the operation receiving unit **13** or the external terminal operated by the user.

In step S110, the control unit **11** controls a lighting state of the lighting unit **15** for each region according to the suction region and the non-suction region identified in step S100. On the inner side of the support portion **20**, the lighting unit **15** is provided for each region of the support portion **20**. Thus, in step S110, the control unit **11** makes the lighting state of the lighting unit **15** corresponding to the suction region different from the lighting state of the lighting unit **15** corresponding to the non-suction region.

In the embodiment, the support portion **20** has a "light transmitting portion" that transmits the light emitted by the lighting unit **15** to the outer side of the support portion **20**.

As a first example, it is assumed that the light transmitting portion is the suction holes **22**. That is, the suction holes **22** also serve as the light transmitting portion.

"To make the lighting states different" means, for example, "to make the lighting colors different". That is, the control unit **11** can turn on the light source corresponding to the suction region with a first color representing the suction region, and turn on the light source corresponding to the non-suction region with a second color representing the non-suction region.

Further, "to make the lighting states different" may mean "to turn on one and turn off the other". For example, the control unit **11** may turn on the light source corresponding to the suction region, and turn off the light source corresponding to the non-suction region.

In addition, "to make the lighting states different" may mean "to make degrees of brightness of lighting different".

For example, the control unit 11 may light the light source corresponding to the suction region brighter than the light source corresponding to the non-suction region.

In addition, "to make the lighting states different" may mean "to make one or the other blink". For example, the control unit 11 may blink the light source corresponding to the suction region and set the light source corresponding to the non-suction region to a state other than blinking.

In addition, "to make the lighting states different" may mean "to make the blinking methods different". For example, the control unit 11 may blink the light source corresponding to the suction region at a first lighting interval representing the suction region, and blink the light source corresponding to the non-suction region at a second lighting interval representing the non-suction region.

The control unit 11 may combine various modes such as color, degree of brightness, blinking, and the like to make the lighting state corresponding to the suction region different from the lighting state corresponding to the non-suction region.

In step S120, the control unit 11 controls the suction mechanism to perform suction targeting the suction region. The execution order of steps S110 and S120 does not have to be as illustrated in FIG. 3. The control unit 11 may start step S120 before step S110, or may start step S110 and step S120 simultaneously.

The inner side of the support portion 20 is divided into internal spaces corresponding to the respective regions of the support surface 21, and the control unit 11 can select to suck or not suck each internal space for each region with the suction pump 16. Thus, in step S120, the control unit 11 may control the suction pump 16 to suck only the internal space corresponding to the suction region.

FIG. 4 illustrates part of the support portion 20. A first region 21a on the support surface 21 and a first internal space 23a corresponding to the first region 21a are simply illustrated by a partial cross-sectional view. A plurality of suction holes 22 passing through the support surface 21 are formed in the first region 21a, and one or more light sources 15a are fixed in the first internal space 23a. The light sources 15a in the first internal space 23a are the lighting unit 15 corresponding to the first region 21a. On the inner side of the support portion 20, such a lighting unit 15 is provided for each region on the support surface 21. When the light source 15a is turned on, the light emitted by the light source 15a is released to the outer side through the suction hole 22. When the first region 21a is part of the suction region, the user can distinguish and recognize the first region 21a, which is part of the suction region in the support portion 20, from the non-suction region because the lighting state of the light source 15a in the first internal space 23a is different from the lighting state of the light source in the internal space of the non-suction region.

The first internal space 23a communicates with the suction pump 16 via a communicating portion 24 and a tube (not illustrated). The dashed arrow in FIG. 4 indicates how the air in the first internal space 23a is sucked into the suction pump 16 through the communicating portion 24.

For example, the suction pump 16 may be disposed one for each partitioned internal space in the support portion 20, and the internal space and the suction pump 16 may communicate with each other on a one-to-one basis. In this case, the control unit 11 may cause the suction pump 16 corresponding to the internal space to suck the internal space corresponding to the suction region.

Alternatively, the suction pump 16 may be configured to be disposed one for all or a plurality of internal spaces in the

support portion 20. In this case, the control unit 11 can set the suction or non-suction state for each of the plurality of internal spaces by opening or closing the tube or the communicating portion 24 that communicates the suction pump 16 to each of the plurality of internal spaces with an individual valve or the like.

In the example illustrated in FIG. 4, a plurality of light sources 15a are disposed at positions corresponding to the plurality of suction holes 22, respectively, in the first internal space 23a. The position corresponding to the suction hole 22 means the position that matches or substantially matches the suction hole 22 in the first direction D1 and the second direction D2. According to this configuration, the light by the light source 15a can be efficiently transmitted to the outer side through the suction hole 22. However, such a configuration is merely an example, and the number of suction holes 22 in the region does not have to match the number of light sources in the internal space corresponding to this region. Also, the position of the suction hole 22 may be shifted from the position of the light source in the internal space.

After going through the processing in the flowchart in FIG. 3, the user places the medium on the support portion 20. At this time, the user can easily identify the suction region on the support surface 21 visually, so that the medium can be placed in the suction region without mistake. Although not illustrated in FIG. 3, the control unit 11 causes the printing unit 17 to perform printing on the medium placed in the suction region of the support portion 20.

FIG. 5A is a diagram for describing a difference in visibility between the suction region and the non-suction region in the first example, and illustrates the support portion 20 viewed from above. In FIG. 5A and FIGS. 5B and 5C described later, the head moving unit 18 and the printing head 19 are omitted, and the support surface 21 and the plurality of suction holes 22 formed on the support surface 21 are illustrated.

In the example of FIG. 5A, the support surface 21 is divided into three regions, the first region 21a, a second region 21b, and a third region 21c, and the internal space as illustrated in FIG. 4 is formed in the support portion 20 corresponding to each of these three regions. The number of regions is not limited to three, and may be two, four, or more.

In the example of FIG. 5A, it is assumed that the first region 21a is the suction region, and the second region 21b and the third region 21c are the non-suction region. In FIG. 5A, the suction holes 22 in the first region 21a are illustrated in white, and the suction holes 22 in the second region 21b and the third region 21c are illustrated in gray to visually represent an example in which the lighting state of the lighting unit 15 corresponding to the suction region is different from the lighting state of the lighting unit 15 corresponding to the non-suction region. In addition, in FIG. 5A, in order to emphasize the suction holes 22 in the first region 21a, the color of the support surface 21 itself, which is not a light transmitting portion, is also expressed in the same gray color as the suction holes 22 in the second region 21b and the third region 21c. A user who sees the support portion 20 illustrated in FIG. 5A can easily recognize that the first region 21a is the suction region and place the medium in the first region 21a.

FIG. 5B is a diagram for describing a difference in visibility between the suction region and the non-suction region in a second example. The way of viewing FIG. 5B is the same as the way of viewing FIG. 5A. Here, in the second example, it is assumed that the light transmitting portion is

the plate surface of the support portion 20, that is, the support surface 21 itself. Specifically, in the second example, the plate member constituting the support surface 21 may be a light-guiding plate or a transparent member such as glass or plastic. According to such a configuration, the support surface 21 itself can guide the light on the inner side of the support portion 20 to the outer side of the support portion 20.

Also in FIG. 5B, it is assumed that the first region 21a is the suction region, and the second region 21b and the third region 21c are the non-suction region. In FIG. 5B, the first region 21a of the support surface 21 is illustrated in white, and the second region 21b and the third region 21c are illustrated in gray to visually represent an example in which the lighting state of the lighting unit 15 corresponding to the suction region is different from the lighting state of the lighting unit 15 corresponding to the non-suction region. A user who sees the support portion 20 illustrated in FIG. 5B can easily recognize that the first region 21a is the suction region and place the medium in the first region 21a.

FIG. 5C is a diagram for describing a difference in visibility between the suction region and the non-suction region in a third example. The way of viewing FIG. 5C is the same as the ways of viewing FIGS. 5A and 5B. Here, in the third example, it is assumed that the light transmitting portion is a member having light guiding properties or light transmission properties that surrounds each region of the support portion 20 in a frame shape region by region. In the example of FIG. 5C, when the support surface 21 is viewed from above, the first region 21a is surrounded by a first frame portion 25a, the second region 21b is surrounded by a second frame portion 25b, and the third region 21c is surrounded by a third frame portion 25c. These frame portions 25a, 25b, and 25c are light transmitting portions and are formed of a light-guiding plate or a member having light transmission properties. According to such a configuration, the frame portions 25a, 25b, and 25c can guide the light on the inner side of the support portion 20 to the outer side of the support portion 20.

A difference between FIG. 5B and FIG. 5C can be explained as a difference in whether each region on the support surface 21 is a member having light guiding properties or light transmission properties as a whole, or a member having light guiding properties or transparency in part. Also in FIG. 5C, it is assumed that the first region 21a is the suction region, and the second region 21b and the third region 21c are the non-suction region. In FIG. 5C, the first frame portion 25a is illustrated in white, and the second frame portion 25b and the third frame portion 25c are illustrated in gray to visually represent an example in which the lighting state of the lighting unit 15 corresponding to the suction region is different from the lighting state of the lighting unit 15 corresponding to the non-suction region. A user who sees the support portion 20 illustrated in FIG. 5C can easily recognize that the first region 21a is the suction region and place the medium in the first region 21a.

Note that, as can be seen from FIGS. 5B and 5C, also in the second example and the third example, the suction holes 22 function as light transmitting portion as in the first example. However, in the second example and the third example, the support surface 21 and the frame portions 25a, 25b, and 25c of the support surface 21 may be formed with light-guiding plates, respectively, so that the light-guiding plate emits light by the light source on the inner side of the support portion 20, and the suction holes 22 themselves may not function as the light transmitting portion.

Further, the control unit 11 may control the lighting state of the lighting unit 15 in accordance with the progress or result of printing on the medium placed on the support surface 21.

As a fourth example, the control unit 11 makes, in the suction region, the lighting state of the lighting unit 15 in a “printing completed region” in which the printing by the printing unit 17 on the medium placed in the suction region is completed different from the lighting state of the lighting unit 15 in a “printing incomplete region” in which printing on the medium is not completed.

FIG. 6 is a diagram for describing the fourth example, and illustrates the support portion 20 viewed from above. In FIG. 6 and FIG. 7, which relates to a fifth example described later, the head moving unit 18 and the printing head 19 are illustrated as in FIG. 2. In the fourth example and the fifth example, the light transmitting portion may be adopted from any of the first to third examples. In FIGS. 6 and 7, the light transmitting portion of the second example described in FIG. 5B is employed.

In the example illustrated in FIG. 6, it is assumed that the control unit 11 determines that the first region 21a and the second region 21b are the suction region, and the third region 21c is the non-suction region in the flowchart in FIG. 25. Thus, in step S110, the control unit 11 makes the lighting state by the lighting unit 15 in the first region 21a and the second region 21b different from the lighting state by the lighting unit 15 in the third region 21c as illustrated in an upper part of FIG. 6. As a result, the user recognizes the first 30 region 21a and the second region 21b as the suction region, and places the medium 30 in the first region 21a and the second region 21b. In step S120, the control unit 11 causes the suction pump 16 to suck the internal spaces corresponding to the first region 21a and the second region 21b, respectively.

Thereafter, the control unit 11 controls the head moving unit 18 and the printing head 19 to start printing on the medium 30. The control unit 11 repeatedly makes the printing head 19 eject ink while moving the printing head 19 40 along the second direction D2, and moves the head moving unit 18 a predetermined distance in the first direction D1, to advance printing on the medium 30. As such printing progresses, a printing image IM is gradually formed on the medium 30.

When printing on a portion of the medium 30 in the first region 21a is completed and the head moving unit 18 advances to the second region 21b, as illustrated in a lower part of FIG. 6, the control unit 11 makes the lighting state of the light source corresponding to the first region 21a different from the lighting state of the light source corresponding to the second region 21b. That is, at the timing illustrated in the lower part of FIG. 6, the first region 21a corresponds to the printing completed region, and the second region 21b corresponds to the printing incomplete region. According to 50 the fourth example described above, the user can easily recognize the region in which the printing is completed and the region in which the printing is not completed in accordance with the progress of printing on the medium 30 sucked on the support portion 20.

As the fifth example, in the suction region, the control unit 11 makes the lighting state of the lighting unit 15 in a “printing normally completed region” in which printing by the printing unit 17 on the medium placed in the suction region is normally completed different from the lighting state of the lighting unit 15 in a “printing abnormally completed region” in which printing on the medium is completed in an abnormal state.

FIG. 7 is a diagram for describing the fifth example, and illustrates the support portion 20 viewed from above. For FIG. 7, the difference from FIG. 6 will be described. The contents illustrated in an upper part of FIG. 7 are the same as the contents illustrated in the upper part of FIG. 6. When printing on the medium 30 placed in the first region 21a and in the second region 21b, which are the suction region, is completed, it is assumed that the control unit 11 determines, for example, printing on a portion of the medium 30 in the first region 21a is normally completed, and printing on a portion of the medium 30 in the second region 21b is completed in an abnormal state. In such a case, when the head moving unit 18 advances to the third region 21c, as illustrated in a lower part of FIG. 7, the control unit 11 makes the lighting state of the light source corresponding to the first region 21a different from the lighting state of the light source corresponding to the second region 21b. In other words, in the example of the lower part of FIG. 7, the first region 21a corresponds to the printing normally completed region, and the second region 21b corresponds to the printing abnormally completed region.

Note that the definition of "printing is completed in an abnormal state" varies. The control unit 11 may determine that printing is completed in an abnormal state, for example, when the head moving unit 18 passes through in a state of running out of ink during printing, when the medium 30 is not properly sucked on the support surface 21 and the medium 30 comes into contact with or abnormally approaches the printing head 19, or when a vibration larger than a predetermined level is detected during printing. According to the fifth example described above, the user can easily recognize, for the medium 30 sucked on the support portion 20, a region in which printing is normally completed and a region in which printing is not normally completed.

It is also possible to combine the fourth example and the fifth example. In this case, the control unit 11 may make the lighting states by the lighting units 15 different from each other in the printing (normally) completed region, the printing incomplete region, and the printing abnormally completed region.

As described above, according to the embodiment, a suction apparatus 10 includes a support portion 20 configured to support a medium, a plurality of suction holes 22 formed in the support portion 20, a suction mechanism, when a side, on which a medium is located, of the support portion is an outer side 20 and a side opposite to the outer side of the support portion is an inner side 20, configured to perform suction from the outer side of the support portion 20 toward the inner side through the plurality of suction holes 22, a lighting unit 15 provided on the inner side of the support portion 20 for each region of the support portion 20, a light transmitting portion configured to transmit light emitted by the lighting unit 15 to the outer side of the support portion 20, and a control unit 11 configured to control the lighting unit 15. The control unit 11 makes a lighting state of the lighting unit 15 corresponding to a suction region in which suction at the support portion 20 is enabled different from a lighting state of the lighting unit 15 corresponding to a non-suction region in which the suction at the support portion 20 is disabled.

According to the configuration described above, the user can easily grasp the suction region in the support portion 20 and place the medium in the suction region without mistake, because the user can visually recognize the difference between the lighting state in the suction region and the lighting state in the non-suction region by the light transmitting portion.

As described above, the light transmitting portion is, for example, the suction holes 22. By having the suction holes 22 that also serve as the light transmitting portion, the support portion 20 can be made into a simple structure.

Further, the light transmitting portion may be a plate surface of the support portion 20, or may be a member having light guiding properties or light transmission properties that surrounds each region of the support portion 20 in a frame shape region by region.

In addition, according to the embodiment, a printing apparatus 10 includes a support portion 20 configured to support a medium, a plurality of suction holes 22 formed in the support portion 20, a suction mechanism, when a side, on which a medium is located, of the support portion is an outer side 20 and a side opposite to the outer side of the support portion is an inner side 20, configured to perform suction from the outer side of the support portion 20 toward the inner side through the plurality of suction holes 22, a lighting unit 15 provided on the inner side of the support portion 20 for each region of the support portion 20, a light transmitting portion configured to transmit light emitted by the lighting unit 15 to the outer side of the support portion 20, a printing unit 17 configured to perform printing on the medium supported by support portion 20, and a control unit 11 configured to control the lighting unit 15, in which the control unit 11 makes a lighting state of the lighting unit 15 corresponding to a suction region in which suction at the support portion 20 is enabled different from a lighting state of the lighting unit 15 corresponding to a non-suction region in which the suction at the support portion 20 is disabled.

According to the configuration described above, the user can easily grasp the suction region in the support portion 20 and place the medium in the suction region without mistake, because the user can visually recognize the difference between the lighting state in the suction region and the lighting state in the non-suction region by the light transmitting portion.

In addition, according to the embodiment, the control unit 11 may make, in the suction region, a lighting state of the lighting unit 15 in a printing completed region in which printing by the printing unit 17 on the medium 30 placed in the suction region is completed different from a lighting state of the lighting unit 15 in a printing incomplete region in which printing by the printing unit 17 on the medium 30 placed in the suction region is not completed.

According to the configuration described above, in addition to being able to recognize the suction region in the support portion 20, the user can identify the printing completed region and the printing incomplete region in the support portion 20.

In addition, according to the embodiment, the control unit 11 may make, in the suction region, a lighting state of the lighting unit 15 in a printing normally completed region in which printing by the printing unit 17 on the medium 30 placed in the suction region is normally completed different from a lighting state of the lighting unit 15 in a printing abnormally completed region in which printing by the printing unit 17 on the medium 30 placed in the suction region is completed in an abnormal state.

According to the configuration described above, in addition to being able to recognize the suction region in the support portion 20, the user can identify the printing normally completed region and the printing abnormally completed region in the support portion 20.

The embodiment discloses not only the apparatus but also various categories of disclosure such as the method in each

11

control process performed by the apparatus and the program 12 that allows the processor to execute the method.

The suction apparatus 10 is not limited to the printing apparatus, and may also be configured without the printing unit 17. That is, the features of the suction apparatus 10 according to the embodiment can be applied in situations and configurations where it is necessary to suck a medium that is a subject of some process other than printing, such as reading, heating, drying, processing, or transporting on a specific table or surface.

What is claimed is:

1. A suction apparatus comprising:

a support portion configured to support a medium and have a plurality of regions;

a plurality of suction holes formed in the support portion; 15 a suction mechanism, when a side, on which a medium is located, of the support portion is an outer side and a side opposite to the outer side of the support portion is an inner side, configured to perform suction from the outer side of the support portion toward the inner side 20 through the plurality of suction holes;

a lighting unit provided on the inner side of the support portion for each region of the support portion;

a light transmitting portion configured to transmit light emitted by the lighting unit to the outer side of the 25 support portion; and

a control unit configured to control the lighting unit, wherein

the control unit makes a lighting state of the lighting unit corresponding to a suction region in which suction at the support portion is enabled different from a lighting state of the lighting unit corresponding to a non-suction region in which the suction at the support portion is disabled.

2. The suction apparatus according to claim 1, wherein the light transmitting portion is the plurality of suction holes.

3. The suction apparatus according to claim 1, wherein the light transmitting portion is a plate surface of the support portion.

4. The suction apparatus according to claim 1, wherein the light transmitting portion is a member having light guiding properties or light transmission properties that surrounds each region of the support portion in a frame shape region by region.

5. A printing apparatus comprising: a support portion configured to support a medium and have a plurality of regions;

a plurality of suction holes formed in the support portion; a suction mechanism, when a side, on which a medium is located, of the support portion is an outer side and a side opposite to the outer side of the support portion is an inner side, configured to perform suction from the outer side of the support portion toward the inner side through the plurality of suction holes;

a lighting unit provided on the inner side of the support portion for each region of the support portion;

a light transmitting portion configured to transmit light emitted by the lighting unit to the outer side of the support portion;

a printing unit configured to perform printing on the medium supported by the support portion; and a control unit configured to control the lighting unit, wherein

the control unit makes a lighting state of the lighting unit corresponding to a suction region in which suction at the support portion is enabled different from a lighting state of the lighting unit corresponding to a non-suction region in which the suction at the support portion is disabled.

6. The printing apparatus according to claim 5, wherein the control unit makes, in the suction region, a lighting state of the lighting unit in a printing completed region in which printing by the printing unit on the medium placed in the suction region is completed different from a lighting state of the lighting unit in a printing incomplete region in which printing by the printing unit on the medium placed in the suction region is not completed.

7. The printing apparatus according to claim 5, wherein the control unit makes, in the suction region, a lighting state of the lighting unit in a printing normally completed region in which printing by the printing unit on the medium placed in the suction region is normally completed different from a lighting state of the lighting unit in a printing abnormally completed region in which printing by the printing unit on the medium placed in the suction region is completed in an abnormal state.
